[57] CLAIM

The ornamental design for a golf tee, as shown and described.

DESCRIPTION

FIG. 1 is a typical top plan view of a golf tee showing my new design;

FIG. 2 is a side elevation thereof, all other sides appearing the same;

FIG. 3 is a typical bottom plan view thereof;

FIG. 4 is a cross section view taken along line 4—4 of FIG. 3; and

FIG. 5 is a side elevation of a further embodiment thereof, all other sides appearing the same.

The broken line showing of the partial golf ball and letters are for illustrative purposes and form no part of the claimed design.
